SMOKING DEVICE

George W. Rehfeld, Manhattan, Kans.

Application April 26, 1952, Serial No. 284,537

2 Claims. (Cl. 131—182)

This invention relates to tobacco smoking devices of the type including a tobacco receptacle, and a stem and mouthpiece interconnected in axial relation therewith. Such smoking devices may require a filter and an insulated tobacco receptacle in order that a cool, clean smoke may be drawn through the mouthpiece.

In my copending application on Smoking Device, Serial No. 143,995, now Patent No. 2,617,427, issued November 11, 1952, I have disclosed a tubular stem forming a filter chamber and which is charged with tobacco from a tobacco receptacle so that the tobacco serves as the filtering material. The pipe structure disclosed in my copending application operates satisfactorily, but care is required in packing the filter chamber in order to provide the proper draft and to prevent spilling of the tobacco from the filter chamber when the ashes are discharged from the tobacco receptacle after the device has been smoked.

It is, therefore, the principal object of the present invention to provide a smoking device of this character with an improved stem and tobacco receptacle to facilitate filling of the filter chamber so that special care need not be required in order to provide the proper draft and so that the tobacco will not be lost from the filter chamber when ashes are expelled from the tobacco receptacle.

It is an object of the invention to provide the head of the stem with a restricted passageway that tapers reversely to the exterior taper of the stem head.

It is also an object of the invention to provide a structure which facilitates discharge of tobacco from the filter chamber when the filtering material must be replaced.

A further object of the invention is to provide a smoking device of the type described wherein the stem is guided throughout the length thereof when the stem is projected into and retracted from the tobacco receptacle when packing the tobacco and controlling the burning thereof.

Another object of the invention is to provide a head on the stem which forms a wedge type seal with the tobacco receptacle and has a forwardly extending rim or lip for effecting removal of ashes and caked material from the tobacco receptacle.

A further object of the invention is to provide the head of the stem with a recess in the forward face to receive the end of a cigarette therein.

In accomplishing these and other objects of the invention hereinafter pointed out, I have provided improved structure, the preferred form of which is illustrated in the accompanying drawing wherein:

Fig. 1 is a perspective view of a smoking device constructed in accordance with the present invention.

Fig. 2 is an enlarged longitudinal sectional view of the smoking device showing the stem and mouthpiece projected into the tobacco receptacle.

Fig. 3 is an end view of the tobacco charging end of the smoking device.

Fig. 4 is an enlarged longitudinal sectional view through the smoking device shown in Fig. 1.

Fig. 5 is a perspective view of the stem and tobacco receptacle of the device shown in Fig. 1, parts of the smoking device shown in spaced coaxial relation with portions of the parts being broken away and in section to better illustrate the construction thereof.

Fig. 6 is a view of the mouthpiece end of the smoking device shown in Fig. 1.

2

Fig. 7 is a perspective view of the mouthpiece and stem of the device shown in Fig. 1, the mouthpiece being shown as removed from the stem.

Referring more in detail to the drawings:

5 1 designates a smoking device embodying the features of the present invention and which includes a substantially elongated cylindrical tobacco receptacle 2, a stem 3 and a mouthpiece 4, all mounted in interconnected axial alignment. The receptacle 2 includes a wall 5 formed of a tubular section of insulating material such as a heat resistant synthetic plastic and having open ends 6 and 7 to receive therein end members 8 and 9. The end members 8 and 9 are preferably formed of light-weight material such as aluminum alloy and have cylindrical portions 10 and 11 that are pressed tightly within the tubular section which forms the insulating wall 5.

The member 8 has a portion 12 that tapers inwardly toward the axis of the members to provide an opening 13 of a diameter adapted to pass the stem 3. The end member 9 has a portion 14 which is open toward the stem end as indicated at 15. It is obvious that the tobacco space 16 in the receptacle 2 thus formed extends the full length of the insulating wall 5 and end member 8. While the projecting portion 12 may be cylindrical, it is preferably tapered as described to retain the burning tobacco.

The stem 3 is also preferably formed of light-weight material such as aluminum alloy and includes a cylindrical portion 17 having a sliding fit within the opening 15. The stem also includes tapered portion 18 corresponding with the tapering portion 14 of the end member 9 to fit therein and provide a wedge-tight seal when the stem is in the position as shown in Fig. 4.

An insert 19, which may be of non-metallic material, is applied within the tapered portion 18 of the stem. The insert 19 has a tapered axial recess 20. The recess 20 communicates with the relatively small axial smoke passage 20' which communicates with a recess 21 in the outer end of the insert 19. The larger end of the axial recess 20 corresponds with the inner diameter of the stem while the smaller end is approximately the diameter of the smoke passageway 20' to cooperate therewith in providing for passage of smoke therethrough and to limit spilling of tobacco from the stem into the smoking space that is provided in the smoke chamber of the tobacco receptacle 2 when the tobacco receptacle is loaded as later described. The insert 19 is pressed into the internal taper of the stem and gives added wall thickness to provide an annular tamping face 22 for tamping tobacco in the tobacco receptacle. The axial recess 21 may be used to receive the end of a cigarette so that the smoking device may be used as a cigarette holder if desired.

The insert 19 may be of a size to permit slight forward projection of the stem to provide an annular scraping lip or rim 23 to facilitate discharge of tobacco from the tobacco chamber.

The opposite end of the stem has a tapered counterbore 24 to frictionally receive a tapered end 25 of the mouthpiece 4. The mouthpiece 4 may be substantially conventional shape and the end 25 closes the adjacent end of the stem. The stem provides a filter chamber 26 having its outer end defined by the insert 19. The filtering material 27 to be contained in the filter chamber may be loose tobacco (Fig. 4).

The mouthpiece 4 has a smoke passageway 28 that connects with the filter chamber 26 and which extends through the bit 29 of the mouthpiece. The bit 29 of the mouthpiece preferably has a transverse width slightly greater than the inner diameter of the smaller end of the member 9 so that when the stem and mouthpiece are in telescoped relation with respect to the tobacco receptacle, the stem and mouthpiece are retained therein but are adapted to be slid through the tobacco receptacle when

pressure is applied in the longitudinal direction of the mouthpiece to force the side edges 30 and 31 of the bit 29 through the smaller end of the tapered portion 14, the end member 9 being of sufficient resiliency to allow the slight distortion necessary to permit the side edges 30 and 31 to slide through the small end of the tapered portion 14 when the bit is to be withdrawn from the tobacco receptacle.

In using the smoking device, the mouthpiece 4 is removed from the stem 3 and loose tobacco is inserted into the filter chamber 26 and is packed therein through the open end from which the mouthpiece was removed. The insert 19 at the forward end of the filter chamber 26 having the tapered recess 20 therein prevents the tobacco from discharging from that end of the filter chamber.

The stem may be removed from the tobacco receptacle by sliding the same forwardly through the open end 13 with sufficient pressure so that the side edges 30 and 31 of the bit portion 29 of the mouthpiece 4 spread the end member 8 sufficiently to allow passage of the mouthpiece portion. After withdrawal of the stem 3 from the receptacle 2, the mouthpiece 4 may be removed and the stem filled with tobacco through the open end thereof. The mouthpiece 4 is then reapplied and the bit end 29 of the mouthpiece is reinserted through the forward end of the tobacco receptacle so that the stem and mouthpiece assembly may be slid through the tobacco receptacle for seating the taper 18 of the stem in wedging contact with the tapered portion 14 of the end member 9.

Tobacco is inserted in the tobacco receptacle through the open end 13 after which the charge of tobacco is compressed within that portion of the tobacco receptacle that is surrounded by the end member 8. This is effected by moving the stem assembly forwardly in the tobacco receptacle with the tamping face 22 pressing against the tobacco. The stem is then returned to again effect a seal of the tapered portion 18 thereof with the end member 9 which leaves a smoke space 32 between the charge 33 of the compressed tobacco within the forward end of the smoking receptacle and the tapered end of the stem (see Fig. 4). The tobacco may then be lighted by applying a flame at the open end 13 and drawing through the smoke passage 28 of the mouthpiece 4.

After a smoke, the ashes are readily discharged from the end member 8 by pushing the stem 3 forwardly with the face 22 and rim portion 23 thereof pressing the remaining tobacco and ashes through the opening 13. The tobacco forming the filtering material remains in the filter chamber 26 of the stem and is not readily displaced therefrom due to the small passageway 20'. The smoking device may, therefore, be carried in the pocket without loss of the tobacco from the filter chamber. To facilitate carrying of the smoking device when empty, it may be telescoped as shown in Fig. 2.

When it is desired to replace the filtering material, the stem and mouthpiece assembly are removed through the end 13 as above described, after which the mouthpiece 4 is withdrawn from the stem 3. The filtering material may then be discharged through that end of the stem by blowing through the opening 20'. The filter chamber of the stem may then be recharged with tobacco, after which the mouthpiece 4 is again replaced and the assembly is reconnected with the tobacco receptacle 2. The device may be used as a cigarette holder by pushing the stem through the tobacco receptacle into the position shown in Fig. 2. The end of a cigarette may then be inserted within the recess 21, after which the stem is moved retractively with respect to the tube receptacle to enclose the cigarette therein while the cigarette is being smoked.

What I claim and desire to secure by Letters Patent is:

1. A smoking device comprising a mouthpiece, a stem, and a tobacco receptacle all interconnected in axial alignment with the tobacco receptacle having an annular wall provided with a tapered portion at one end engaging a tapered end on the stem and said receptacle having an open opposite end of slightly smaller inner diameter

than the larger diameter of said tapered end of the stem and through which tobacco is inserted into the tobacco receptacle, said stem having a filter chamber therein for containing a filtering material and said tapered end having a smoke passageway communicating with the tobacco receptacle, said stem being reciprocable within the receptacle and the tapered portion of said stem having an annular tamping face encircling the smoke passageway adapted to dislodge burnt tobacco from the receptacle and to pack tobacco within the open end portion of the receptacle upon reciprocation of the stem to and from a position with the tapered portion of the stem engaging the tapered portion of the receptacle, and said mouthpiece having an end removable from the end of the stem opposite the tapered end thereof to permit the insertion of filtering material into the filter chamber of said stem without removing the stem from the receptacle and replaceable to retain the filtering material, and the opposite end of the mouthpiece having side portions slightly wider than the smaller diameter of said tapered portion of the receptacle adapted to frictionally engage therewith and to cooperate with the opposite end of the receptacle when the stem is telescoped within the receptacle to retain the stem in said telescoped position.

2. A smoking device comprising a mouthpiece, a stem, and a tobacco receptacle all interconnected in axial alignment with the tobacco receptacle having an annular wall provided with a tapered portion at one end engaging a tapered end on the stem and said receptacle having an open opposite end through which tobacco is inserted into the tobacco receptacle, said stem having a filter chamber therein for containing a filtering material and said tapered end having a smoke passageway of smaller diameter than the filter chamber for communicating the filter chamber with the tobacco receptacle, said stem being reciprocable within the receptacle and the tapered portion of said stem having an annular tamping face encircling the smoke passageway and a surrounding annular lip engaging the wall of the receptacle to dislodge burnt tobacco from the receptacle and to pack tobacco within the open end portion of the receptacle upon reciprocation of the stem to and from a position with the tapered portion of the stem engaging the tapered portion of the receptacle, said mouthpiece having an end removable from the end of the stem opposite the tapered end thereof to permit the insertion of filtering material into the filter chamber and replaceable to retain the filtering material, the mouthpiece having a bit portion of slightly greater width than the tapered portion of the receptacle adapted to cooperate with the tapered end of the stem in retaining the stem in connection with the receptacle, and said tapered portion of the receptacle being yieldable to permit removal of the stem.
